COMBINATION DISPOSABLE SYRINGE UNIT

Arthur E. Smith, Los Angeles, Calif.

Application September 20, 1947, Serial No. 775,193

2 Claims. (Cl. 128—218)

1

This invention relates to a combination disposable syringe unit.

The general object of the invention is to provide a syringe of the disposable type which may be used either for the preparation and injection of a freshly mixed drug and vehicle, or for the injection of a previously prepared drug containing solution or mixture.

An example of the drugs in a freshly prepared solution would be penicillin or a local anaesthetic such as procain hydrochloride, while an example of an already mixed medicinal compound would be penicillin-oil-wax and vaccines.

A more specific object of the invention is to provide a syringe including a novel liquid holding plunger member.

Another object of the invention is to provide a novel front member for a syringe.

A further object of the invention is to provide a syringe including a liquid holding plunger member, wherein novel means is provided for causing the liquid in the plunger to move into the barrel.

A further object of the invention is to provide a syringe having novel means for holding a drug in position and for, at will, placing the drug in solution in a vehicle carried by the syringe.

Other objects and advantages of my invention will be apparent from the following description taken in connection with the accompanying drawings, wherein:

Fig. 1 is a side elevation of a syringe embodying the features of my invention;

Fig. 2 is a fragmentary, enlarged, central, sectional view, showing the syringe;

Fig. 3 is a central, sectional view, showing the syringe after the solution is prepared;

Fig. 4 is a fragmentary, central, sectional view, showing the needle moved to pierce the diaphragm;

Fig. 5 is a fragmentary, central, sectional view, showing the front end of a modified type of my invention, and

Fig. 6 is a view similar to Fig. 4, showing the rear end of the modified type.

Referring to the drawing by reference characters, I have shown my invention as embodied in a syringe which is indicated generally at 10.

As shown, the syringe includes a barrel 11 having a plunger 12 slidable therein. The barrel and plunger may be made of plastic or other suitable material. Upon the outer end of the plunger I mount a rear end member which is indicated generally at 13 and which may be made of flexible rubber. The rear end member includes a body 14 disposed within the plunger 55

2

and a flange 15 which extends outwardly beyond the barrel and forms a finger engaging portion. The rear end member includes an axial recess 16 which is closed at its inner end by a diaphragm 17 and communicates with a concave portion 18 which latter may be engaged by the thumb of the operator.

In some instances it is necessary to bleed the interior of the plunger and to take care of this I arrange a slit 19 in the diaphragm 17. This slit, due to the resiliency of the material in which it is arranged, permits passage of air into the plunger while preventing passage of fluid therefrom.

On the front of the plunger I arrange a piston, indicated generally at 20. As shown, the piston includes a body 21 arranged within the plunger and a forward portion 22 which has spaced peripheral piston ring forming beads 23 thereon. The piston is preferably made of soft rubber and includes an axial recess 24 which is closed at the forward end of the piston by a convex, walled diaphragm 25. This diaphragm 25 has a slit 26 therein and the construction is such that fluid may be withdrawn from the plunger through the slit 26 but cannot be readily forced into the plunger through the slit.

The syringe barrel 11 may be provided with an inwardly directed flange 27 arranged at the outer end thereof and engageable by the innermost bead 23 to prevent full withdrawal of the plunger from the barrel by a careless operator.

Upon the barrel, adjacent to the piston, I arrange a front member 28, which like the piston, may be made of rubber. The front member includes a body 29 having a forwardly projecting cylindrical portion 30 from which a reduced tip 31 extends. The front member includes an integral skirt 32 which is spaced from the body 29. The skirt has a peripheral flange 33 thereon, which may be grasped by the fingers of the operator. The front member includes an axial outer recess 34, and an inner axial recess 35 with a diaphragm between the recesses.

My syringe is adapted for use with previously prepared solutions or for the preparation of fresh solutions. When fresh solutions are to be prepared, I place a medicinal preparation, shown as a tablet 37, in the recess 35 and I place a vehicle for this tablet in the plunger 12.

When the preparation is in the recess 35 it is protected against contamination from outside sources and is maintained out of contact with its vehicle until the operator desires to prepare the solution.

Upon the tip 31 I arrange a cap 39, the skirt

40 of which slides upon the tip, while the body 41 is formed about a needle 42 and a protuberance 43 on the needle. The inner end of the needle is preferably sharpened as at 44 and is closely adjacent to, but does not pierce, the diaphragm 36 when in normal position.

The needle is maintained sterile and premature piercing of the diaphragm by the needle is prevented by the arrangement of a closure 45 which engages the projecting portion 30. The closure includes a rubber front member 46 which has a recess 47 in which the sharpened front end 48 of the needle is inserted.

When the syringe is to be used, the operator grasps the rear end member 13 of the plunger and pulls the plunger rearwardly. The partial vacuum produced in the barrel causes liquid within the plunger to open the valve 26 as the liquid passes into the barrel. The valve 19 also opens to supply atmospheric air to the interior of the ampule. In many instances the valve 19 may be omitted, depending upon what amount of liquid is to be withdrawn from the plunger.

After the desired vehicle has passed into the barrel, the closure 45 is removed and the cap 39 is moved along the tip 31, causing the sharpened end 44 of the needle to pierce the diaphragm 36, whereupon the syringe is ready for use.

In Figs. 5 and 6 I show a modification of my invention wherein similar parts are designated by single primed reference characters.

In the modification the piston 20' is shown as extended so that the front end thereof substantially covers the inner face of the end member. The piston is provided with a cavity 49 in which a medicinal preparation 50, similar to the preparation 37, is placed. The end of the piston is provided with a slit 51 which forms a valve. The slit 51 is aligned with a recess 52 which is similar to, but smaller than, the recess 35.

The rear end of the plunger as shown in Fig. 6 is provided with a cap 53 which includes a recess 54 receiving the flange 27' on the plunger 12'. The cap 53 includes a skirt 55 which is of the same diameter as the outer diameter of the barrel 11'. A seal 56, which may be made of paper or similar material, serves to hold the plunger in forward position where the piston about the cavity 49 engages the inner face of the front member to protect the preparation 50. The cap 53 includes a recess 57, diaphragm 58 and a valve slit 59, similar to the parts 16, 17 and 19 previously described.

In use of the modified syringe the seal 56 is broken and the plunger is withdrawn; the operation is then similar to that previously described. The present application discloses a construction similar to the construction in applicant's copending applications Serial Nos. 775,192 and 775,194, both filed September 20, 1947.

In the present application the claims are directed specifically to a syringe wherein the ampule is provided with a front member which has a recess therein and wherein the recess is sealed by the piston plunger. In application Serial No. 775,192 the claims are directed to the front member closure with the diaphragm therein; while in application Serial No. 775,194 the claims are directed broadly and specifically to a syringe wherein the piston plunger is provided with a valve permitting fluid to flow from the rear of the piston plunger to the front thereof.

The subject matter disclosed in this application is similar to the subject matter disclosed in my copending application Serial No. 775,194, filed September 20, 1947.

From the foregoing description it will be apparent that with my invention the active medicinal ingredient is sealed in a dry state, separate from the solution until a few seconds before injection. The solution is prepared by the mere act of preparing the syringe for use. Thus, full drug potency and freedom from toxicity due to drug deterioration is secured. Also, the same unit may be used for the scientific administration of already prepared medicinal compounds by merely preparing the syringe for use.

Having thus described my invention, I claim:

1. A syringe including a barrel, a plunger shiftable in said barrel, said plunger comprising an ampule having a closure at the rear end thereof, said closure including a one-way valve permitting passage of air from the atmosphere into the ampule but preventing passage therethrough from the ampule, a piston stopper in the front end of the ampule, said piston stopper having a recess and having an integral portion forming an outer wall for said recess, said outer wall having a slit therein, said piston stopper being made of flexible rubber permitting the slit to open to permit passage of fluid from the ampule while preventing passage into the ampule, said barrel having a front member thereon, said front member having a recess, a drug in said recess, the wall of said front member about said recess engaging the piston stopper about the valve therein to seal the latter against opening, and a needle mounted on said front member and communicating with said front member recess.
2. A syringe including a barrel, a plunger shiftable in said barrel, said plunger comprising an ampule having a closure at the rear end thereof, said closure including a one-way valve permitting passage of air from the atmosphere into the ampule but preventing passage therethrough from the ampule, a piston stopper in the front end of the ampule, said piston stopper having a recess and having an integral portion forming an outer wall for said recess, said outer wall having a slit therein, said piston stopper being made of flexible rubber permitting the slit to open to permit passage of fluid from the ampule while preventing passage into the ampule, said barrel having a front member thereon, said front member having a recess, the wall of said front member about said recess engaging the piston stopper about the valve therein to seal the latter against opening, said front member having an outwardly opening recess coaxial with the first recess therein, a diaphragm between said front member recesses, a needle mounted on said front member and extending through said diaphragm and communicating with said front member recess, said piston stopper having a cavity in the outer face thereof and a medicinal preparation in said cavity, the wall of the piston stopper about the cavity engaging the inner wall of the front member.

ARTHUR E. SMITH.
